UNITED STATES PATENT OFFICE.

WALTER R. CLOSE, OF BANGOR, MAINE.

IMPROVEMENT IN WATER-WHEELS.

Specification forming part of Letters Patent No. 57,089, dated August 14, 1866.

To all whom it may concern:

Be it known that I, WALTER R. CLOSE, of Bangor, in the county of Penobscot and State of Maine, have invented an Improved Water-Wheel; and I do hereby declare the same to be fully described in the following specification, and represented in the accompanying drawings, of which—

Figure 1 is a top view, Fig. 2 a side elevation, and Fig. 3 a transverse section, of it.

The said water-wheel is what is termed a "flutter-wheel," and is intended to be cast in one piece of metal and so as to be readily fixed to a vertical wooden shaft.

For this purpose the central part of the wheel is to consist of a metallic cylindrical tube, *a*, having a flat annular flange, *b*, projecting from its bottom. A series of floats or wings, *c c c e*, extend from the tube *a* in manner and are formed as represented in the drawings, and at their lower ends they are joined to the flange *b*, and also to a flat annulus, *d*, which is concentric with the flange *b*. Those parts of the annulus *d* which are between the wings are curved or arched, as shown in Fig. 2, the purpose of such arch being to enable the ring *d*, while the water-wheel is in revolution, to exert an action on the water such as

will tend to cause it to press the wheel upward more or less, and thus relieve the step and pivot of the water-wheel shaft from the friction which would otherwise be induced by the weight of the wheel.

By making the wheel with the tubular part *a*, it can be fitted to a wooden shaft, and by applying to the tube *a* the flange, which projects from it, I not only prevent the tube from being cracked, but give increased support to the wings, each of which, where it crosses the outer annulus, is bent so as to extend across the same at right angles to it. This bend of each wing is shown at *e*, and causes the water, when it first strikes the wheel, to do so square to the bucket, whereby its useful effect is increased over what it would be were the curve of the wing continued across the bucket.

I claim—

The improved water-wheel, made substantially as described—viz., with the arched annulus, the series of curved and bent wings, and the shaft-tube, or the same and its flange, arranged as set forth.

W. R. CLOSE.
